UNITED STATES PATENT OFFICE.

EMIL FREINER, OF BUFFALO, ASSIGNOR TO FRANCISCA FREINER, OF HAMBURG, NEW YORK.

MUSICAL INSTRUMENT.

SPECIFICATION forming part of Letters Patent No. 449,439, dated March 31, 1891.

Application filed January 2, 1890. Serial No. 335,572. (No model.)

To all whom it may concern:

Be it known that I, EMIL FREINER, of Buffalo, in the county of Erie and State of New York, have invented certain new and useful 5 Improvements on Mechanical Musical Instruments; and I do hereby declare that the following description of my said invention, taken in connection with the accompanying sheet of drawings, forms a full, clear, and exact 10 specification, which will enable others skilled in the art to which it appertains to make and use the same.

This invention has general reference to improvements in mechanical musical instruments, and especially that class of instruments called "metallophones;" and it consists, essentially, in the novel and peculiar combination of parts and details of construction, as hereinafter first fully set forth and 20 described, and then pointed out in the claims.

In the drawings already mentioned, which serve to illustrate my said invention more fully, Fig. 1 is a plan of my newly-invented metallophone. Fig. 2 is an end elevation of 25 the same. Fig. 3 is a plan of a portion of the roller, illustrating the mechanism for shifting the said roller longitudinally. Fig. 4 is a sectional plan of the crank for operating this device.

30 Like parts are designated by corresponding letters of reference in all the figures.

The object of this invention is the production of a cheap mechanism for mechanically operating the musical instrument known by 35 the name of "metallophone," and which consists of a series of metallic plates of different length and thickness properly "pitched" to the musical scale, and in playing struck with a hammer, usually made of wood. To attain 40 this result I construct my mechanical musical instrument substantially of a base A, having two standards B B', the first mentioned of which is provided with two laterally-projecting brackets C C', having bearings for a shaft 45 D, carrying a worm E, engaging a suitably-constructed wheel F, fixed upon a spindle f, journaled in a bearing f' in said standard B, said wheel F being affixed to one end of a roller T, which said roller has on its opposite 50 end a further shaft t, revolving in a bearing b in the standard B', so that said roller T may

revolve freely within said bearings and at the same time move longitudinally, as hereinafter to be referred to. Within the standard B is further journaled a spindle L', (see Fig. 3,) carrying on one end a hand-wheel L and a hand or pointer U, and near the other end a step-wheel K, which said step-wheel has in its rim notches e and projecting from its face an annular rim k, the edge of which is provided with a series of step-like offsets k', arranged in relation to the shaft f in such manner that the latter bears with its end upon one or the other of said steps k', while a spring t' on the end of the shaft t presses said shaft f 65 against the face of one of these steps, as clearly shown in Figs. 1 and 3.

To the side of the standard B is pivoted a lever H, in about its middle, upon a fulcrum h, one arm of said lever carrying a roller J, 70 engaging in the notches e in the wheel K, while the other opposite end connects by means of a connecting-rod I with the key-board M at i. This key-board M consists of an L-shaped bar having on both of its ends 75 lugs to receive the pivots m, passing through the legs of the standards B B', so that said key-board may move around said pivots m. It has, furthermore, upwardly-projecting lugs x, Fig. 2, which receive a long rod n', acting 80 as a pivot for the keys N, the upwardly-projecting ledge n of said key-board being slotted for the passage and guidance of said keys. The keys N are of substantially S shape, the portion projecting forwardly beyond the key- 85 board having an incline v, while the rearwardly and upwardly passing portion is bent and turned to form the shank N', which carries on its extremity a preferably wooden ball O by means of a screw o, said ball being 90 in its normal position somewhat above the metallic plate P. There are in this instrument a suitable number of these keys corresponding to the number of plates P used, and the shanks of all these keys rest upon a support Q, having on its upper edge an elastic strip or cushion q, as illustrated in Figs. 1 and 2. Each of these keys has also a spiral spring S to pull the said keys downwardly upon the cushion q. The metallic plates P 100 are placed upon a sounding-board R, a cushion r being placed between the said plates

and the sounding-board to permit of an undisturbed vibration of the plates whenever struck by the hammers O, while said plates P are retained in position by pins p in the usual manner. The sounding-board R is supported upon the base A by means of suitable studs R'R', as clearly shown in Fig. 2.

Around the periphery of the roller T and in concentric rows are placed pins V, which engage the inclines v of the keys N whenever the said roller is revolved in a suitable direction, thereby depressing the end of the keys carrying these inclines and lifting the hammers O, which will drop as soon as the said pins have passed the inclines, they being assisted in this by the spiral springs S. The velocity attained by these hammers in their downward movement overcoming the rigidity of the shanks N' causes them to strike the plates P, and thereby to vibrate them, causing them to sound their respective notes, so that any musical piece may be played upon this instrument by arranging the pins V in the roller T correspondingly. The roller T is revolved by turning a crank G on the end of the shaft D, which shaft moves said roller by its worm E engaging the wheel F.

The instrument shown and described is arranged to play eight different pieces, (more or less may be played by a suitable arrangement of the parts,) this being accomplished by the mechanism consisting of the step-like wheel K, against which the end of the spindle f revolves. By turning the hand-wheel 35 L, the steps k' of the wheel K will move the roller T longitudinally step by step to eight different positions, there being also a corresponding number of rows of pins V in the periphery of said roller and each representing a musical piece; but since the change from one to the other piece may be made at any point of the roller T between the beginning and the end of a piece, it is necessary to depress the key-board M to remove the inclines v of the keys out of the range of the pins V. This is accomplished by the lever H and connecting-rod I in such a manner that when the hand-wheel L is revolved the roller J rises upon the periphery of wheel K and thereby depresses the key-board M in an obvious manner. This takes place just before the steps k' in the face of said wheel K push the spindle f longitudinally, while as soon as the latter has taken place the said roller J 50 will drop into the next succeeding notch e, and thereby return the key-board into its normal position.

Upon the shaft L' there is a hand U, and upon the face of the end board X of the instrument there are placed marks or numbers (the pointer is shown to indicate the third piece in Fig. 2) to indicate the respective musical piece to which the instrument is set.

It is obvious that the entire mechanism may 65 be placed into or surrounded by a suitable case, which may be ornamental, as is customary with instruments of all kinds.

In instruments of the kind described it is necessary to guard against the roller T being revolved in the wrong direction, the proper direction of revolution being marked by an arrow in Fig. 2. This is usually accomplished by either a brake on the crank-shaft, a ratchet and pawl thereon, or by screwing the crank onto the said shaft, so that by turning the 75 crank in the wrong direction this crank will unscrew from said shaft. These devices are either costly or otherwise unsatisfactory, and to overcome the objections to which they are open I locate upon the shaft D two collars d 80 and place the crank G between them. The eye of this crank is open, and a pawl g is pivoted to said crank, so that it may engage one or more notches a in the said spindle D by a spring g' acting upon said pawl. This mechanism is at once extremely simple and very efficient and has the advantage that the crank may be readily removed to prevent meddling with the instrument by lifting the pawl g.

It will be further observed that the wheel 90 K, having in its face the series of successive steps connected by inclines k'', has from the highest step in the same to the lowest one a deep step k''', corresponding in height to the aggregate height of all the steps, so that the 95 wheel K, when revolved so that the spindle f is on the highest step, it will, if the motion of said wheel K is continued, return to the lowest step by said deep step k''', this result being accomplished by the spring t', already mentioned, acting upon the shaft t, and through it and the roller T upon the shaft f, in an obvious manner.

The star-wheel F is of a width corresponding to the rise of the steps k', so that no matter at what position the roller T may be said star-wheel will be in mesh with the worm E.

Having thus fully described my invention, I claim as new and desire to secure to me by Letters Patent of the United States—

1. In mechanical musical instruments, the mechanism for moving the roller (carrying the pins) longitudinally, consisting of a spindle carrying a wheel having in its face a series of steps jointed by inclines, in combination with the pin-roller having its spindle bearing against said steps, whereby by revolving said step-wheel the pin-roller is moved longitudinally, as and for the object set forth.

2. In mechanical musical instruments, the combination, with the mechanism for moving the pin-roller longitudinally, of mechanism for depressing the key-board with its keys prior to moving said pin-roller and returning the key-board to its normal position as soon as the longitudinal movement is completed, as set forth.

3. In mechanical musical instruments, the combination, with a base having standards, as described, of the shaft D, having the worm E, the pin-roller T, having the shaft f and star-wheel F, the shaft L', provided with the hand-wheel L and the notched wheel K, having in its face the series of steps k', the lever

H, having the roller J, engaging the notches in said wheel K, the connecting-rod I, and the key-board M, with its keys, the whole being constructed and combined to operate in conjunction with suitable metallic plates, as and for the object set forth.

4. In metallophones having a series of metallic bars struck by hammers, as described, mechanism for lifting and dropping said hammers, consisting of a roller having on its periphery a series of concentrically-arranged pins engaging keys, having inclined ends on one end and the shanks fitted with balls on the other end, means for revolving said roller, and further means for moving the same longitudinally and returning the same as soon as the lateral movement of the roller for chang-

ing the tune is completed, and mechanism for automatically depressing the key-board before the said roller is being moved longitudinally, as and for the purpose set forth. 20

5. In mechanical musical instruments, the combination, with the crank-shaft, of a crank having a pawl engaging a notch in said main shaft, whereby said shaft may be revolved in one direction only, as and for the purpose set forth. 25

In testimony that I claim the foregoing as my invention I have hereto set my hand in the presence of two subscribing witnesses.

EMIL FREINER.
